Application April 27, 1932, Serial No. 607,814

35 Claims. (Cl. 179—18)

This invention relates to telephone systems in general and particularly to telephone systems in which connections are completed through the medium of automatic switches. The object of the 5 invention is the provision of new and improved circuits and apparatus for use in systems of the above type for supplying telephone service to small groups of stations.

10 General description

Separate exchanges or central offices commonly known as sub or satellite offices are usually installed to supply telephone service to small groups of stations, when for economic or other 15 reasons, it is impractical to connect the stations individually with the nearest main office. With the equipment heretofore available for installation in such offices, it has been found that the average cost per line of the equipment 20 tends to increase greatly as the number of stations served by the office decrease. This increased cost is due, largely, to the necessity of installing a complete set of power equipment including, for example, ringing current and tone 25 generators, battery charging equipment, etc., regardless of the size of the office.

Arrangements have been suggested whereby the power equipment at a main office could be made to serve a sub-office as well. So far as applicant 30 is aware, prior systems employing this arrangement have not been entirely satisfactory due to their inability to provide service of a quality acceptable for general use. In order to have a general application a system must be able to handle more than one call at a time and prior 35 systems of the type under consideration have not been able to do this. It is also desirable that connections be guarded against intrusion by other subscribers and this has not been possible 40 in prior systems as far as subscribers in the same sub-office are concerned.

The present invention is designed to eliminate the objectionable features of the prior systems. 45 Switching apparatus is provided at the sub-office for handling a plurality of simultaneous calls. The switching apparatus, which consists, mainly, of simple stepping switches, operates on low voltage current supplied by a storage battery 50 at the sub-office. This storage battery is the

only item of power equipment required at the sub-office. Ringing current and tone current as well as charging current are supplied from the main office to which the sub-office is connected. The arrangement for handling simultaneous calls 5 in a system of the above type constitutes one of the main features of the invention.

Another feature of the invention resides in the arrangement for simultaneously operating a switch in the sub-office and a switch in the main 10 office under control of impulse generating apparatus located at the main office. The first-mentioned switch hunts for a calling sub-office line and the latter switch identifies the line for 15 metering and guarding purposes.

Another feature of the invention consists in the provision of a selective switch which is adapted to cooperate with either of several finder switches to complete connections between sub-office subscribers' lines. This switch is adapted 20 to be controlled indirectly by a calling subscriber through the medium of registering and impulse sending means located at the main office.

Another feature of the invention relates to the arrangement whereby the testing for the idle or 25 busy condition of sub-office lines is carried out by equipment located at the main office. An incidental feature is the further arrangement whereby the test for an idle sub-office switch is carried out by equipment at the main office in 30 the case of attempted connections between two sub-office subscribers' lines.

There are various other features relating to the novel circuit organizations employed in carrying out the functions of the different pieces of 35 apparatus constituting the invention. These features and others not specifically mentioned will be described in detail hereinafter, reference being had to the accompanying drawings.

40 Description of drawings

The accompanying drawings comprising Figs. 1 to 6, inclusive, show representative circuits of a telephone system comprising a main office and a sub-office embodying the features of the invention. 45 The system disclosed is designed to supply telephone service to a group of ten stations and to handle two simultaneous calls. It will be appreciated, however, that this particular system is shown to merely illustrate the features of the 50

invention and that these features may be readily applied to systems supplying telephone service to larger groups of lines and adapted to handle any reasonable number of simultaneous calls.

5 Referring now to the drawings, Figs. 1 and 2 show switching apparatus located at a sub-office. Figs. 3, 3A, 4, and 5 show apparatus located at a main office and cooperating with the apparatus shown in Figs. 1 and 2. Fig. 6 is a layout 10 diagram showing the manner in which the various sheets of drawings are to be arranged to illustrate the inter-relationship of the various circuits.

In Fig. 1 there is shown a finder-connector 15 switch FC which operates as a line finder for calls originating on sub-office lines and a connector for calls incoming to such lines. This switch is of the well-known rotary type whose wipers move in one direction only. A contact bank consisting of eleven contact sets is provided. Ten contact sets are assigned to the ten sub-office lines and the eleventh set serves as the normal or home position of the switch wipers. The switch terminates one of the two trunks connecting the 20 sub-office with the main office. Associated with this switch is a revertive connector shown in Fig. 2 over which connections are completed to called lines which terminate in the same sub-office as the calling line. The connections to this latter 25 switch are shown in the lower right-hand corner 30 of the drawings.

Two of the ten sub-office lines accessible to switch FC have been shown in Fig. 1, namely, the lines extending to stations T3 and T7. These 35 lines terminate, respectively, in the third and seventh contact sets of the bank of switch FC. The lines for the other substations terminate in other bank positions. Associated with each line is an individual cut-off relay of the relay group 40 LR shown in the upper left-hand corner of the drawings. A distributor relay group DR is common to all of the sub-office lines and controls the allotment of calls to the trunks and associated finder connectors.

45 Fig. 2 shows the revertive connector RC previously referred to. This switch is mechanically similar to switch FC and has access to the various sub-office lines in corresponding positions of its bank. The circuit connections for the finder- 50 connector associated with the second main office trunk are shown immediately above switch RC. The finder-connector has not been shown, as it is exactly the same as the finder-connector FC and the circuit connections will be readily understood by referring to Fig. 1.

55 Figs. 3 and 3A show the relay equipment comprising the repeater associated with the first trunk connecting the main office and sub-office. The trunk in the sub-office terminates at the 60 left side of Fig. 3. An outgoing trunk extends from the right of Fig. 3A to a line switch LSW. Included in the repeater are a group of impulse generating relays and a group of counting relays which will be described in detail hereinafter.

65 The lineswitch LSW shown in Fig. 3A may be of any well-known and suitable type and has access to the regular switch train at the main office. The switch train has not been shown as it may be of any well-known type, for example, such as 70 that disclosed in the co-pending application of J. Wicks, Serial No. 395,832, filed April 16, 1931.

75 Referring now to Fig. 4, auxiliary switches AS1 and AS2 are associated with repeater R. These switches are of the rotary type provided with eleven position banks of which ten positions are

assigned to sub-office lines and the eleventh position serves as a normal or home position for the wipers. Both of these switches are operated under control of impulse generating relays of repeater R. Switch AS1 operates in synchronism 5 with the finder-connector FC at the sub-office and serves to locate and identify a calling line. Switch AS2 operates in synchronism with revertive connector RC in local calls between sub-office subscribers and in synchronism with finder-connector FC in incoming calls to the sub-office. 10

Fig. 5 shows an auxiliary switch AS3 which is associated with repeater R and the auxiliary switches shown in Fig. 4. This switch is mechanically similar to the first-mentioned auxiliary 15 switches. The switch operates as a counting and marking switch at different stages of a connection. For example, during the establishment of a connection it controls certain counting relays in repeater R which determine the routing of a 20 call. After a call has been definitely identified as for a sub-office subscriber for example, the switch then tests for the busy or idle condition 25 of a revertive connector RC at the sub-office over which connections between the sub-office subscribers are completed in calls of this type.

In Fig. 5 there is also shown a group of line 30 relays LRI and a portion of a contact bank accessible to local and tool connectors of the main office. The line relays are associated individually with the various sub-office lines. A set of contacts in the connector bank is assigned to each sub-office line, these contacts appearing in the same order as the lines terminate in the bank of the finder-connectors at the sub-office. 35

In the upper-left-hand corner of Fig. 5 the repeater and auxiliary switches associated with the second trunk connected in the main and sub-office have been shown diagrammatically. The 40 circuits of this equipment are exactly the same as shown in Figs. 3, 3A, 4, and 5, except for the starting chain circuit. A sufficient amount of the latter circuit has been shown to permit the arrangement to be readily understood. The connection to the banks of the auxiliary switches 45 which for convenience have been designed 2AS1, 2AS2, and 2AS3 are shown in the left-hand portion of Fig. 4.

Brief description

The layout of the system disclosed is generally 50 similar to that ordinarily used in sub-office systems. The sub-office lines are assigned a block of ten consecutive numbers in one of the main office hundred groups. As the instant system is a five digit system, it is apparent that there will be some main office lines with numbers whose first three digits are the same as corresponding digits of the sub-office numbers. Provision is, therefore, made for releasing the branch connection set up over the main office switches only after a fourth digit has been dialled and definitely identifies the call as for a sub-office line. In the case of calls to main office subscribers, such calls may be identified by any one or more of the first four digits. No further digits are registered after a call is definitely identified as for a main office line. 55

In the particular system shown, the sub-office 60 lines are assigned numbers 24511 to 24510. In the case of calls originating in the sub-office, the digits 2451 are registered to identify the call as for a sub-office line and the final digit is then registered to identify the particular line wanted. 65

Main office subscribers dial the complete sub-office line number thereby setting the connector on a set of contacts assigned to the wanted line. The calling subscriber does not dial over the sub-office trunk. The setting of the main office connector marks the wanted line and apparatus associated with the trunk transmits impulse to set the sub-office switch accordingly.

The operations involved in establishing various connections in the system under consideration will now be described briefly. Upon the initiation of a call on a sub-office line, the distributing relay equipment will operate to allot the call to one of the finder connectors, for example, finder connector FC. The impulse generating apparatus at the main office will be started in operation and will transmit impulses to the finder connector and the auxiliary switch AS1 associated with the trunk at the main office. These two switches operate in synchronism until the wipers of the finder connector engage the contacts of the calling line. The impulsing is then stopped and the repeater is prepared for the receipt of dialled impulse. A connection is now extended over the outgoing trunk and line switch LSW to an idle first selector in the main office. This selector returns the dial tone to the calling subscriber to indicate that the equipment is in readiness to respond to dialling. The subscriber then dials the number of the wanted line. If the called subscriber is a main office subscriber, the associated apparatus for completing the call in the sub-office will be temporarily disabled and the impulses will be transmitted to the main office switch train. The manner in which the destination of the call is identified is generally similar to that employed in the so-called switching selector repeater circuit. The auxiliary switch AS3 responds to each series of impulses until a series is received which definitely indicates that the call is for a main office subscriber. Each series of impulses registered on switch AS3 operates either one of the counting relays of the repeater or the switch through relay which controls the switching through of the connection to the main office. In the case of a call to another sub-office subscriber, switch AS3 brings about the operation of the counting relay necessary to release the main office connection and to prepare the switch in the sub-office to complete the connection therein. The impulse generating relays reoperate and transmit impulses over the trunk to set switch RC in accordance with the setting of switch AS3. Switch AS2 operates in synchronism with switch RC, stops the impulsing when the proper line has been found, and proceeds to test the line for its idle or busy condition. In case the line is idle, ringing current is sent out from repeater R. When the called subscriber answers a connection is completed between the calling and called subscriber over the local equipment at the sub-office. Upon the subscribers hanging up at the termination of a connection, the finder-connector will be restored to normal under control of the impulse generating relays. Auxiliary switches AS1 and AS2 will also restore to normal in synchronism with the sub-office switches. Auxiliary switch AS3 and switch RC will restore to normal under a self-controlled circuit.

In the case of calls from a main office subscriber to a sub-office subscriber, a connection will be extended over the regular main office switch train including a connector to the set of bank contacts associated with the wanted sub-

office line. The impulse generating relays of the repeater will function and operate finder-connector FC and auxiliary switch AS2 in synchronism until the latter switch finds the contacts marked in the connector banks. This brings both switches to rest on the contacts associated with the wanted sub-office line which is then signalled in the usual way by ringing current from the calling connector. At the termination of the connection the switches are restored to normal as in the preceding call.

Toll calls may be extended to sub-office subscribers over a toll switch train in substantially the same manner as local calls. In this case, however, if the called line is busy, the toll connector will return either a local or toll busy tone to the operator in the usual manner. If the called line is locally busy, the operator may cause the connector to establish a temporary talking connection with the wanted subscriber. The operator may request the wanted subscriber to terminate the local connection whereupon the toll connection can be established in the well-known manner. In case no switches are available for establishing a connection to the sub-office and the wanted subscriber is not engaged in one of the connections which are employing these switches, the calling toll operator will receive the busy tone in the usual manner. On attempting to cut-in on the connection, and offer the call to the sub-office subscriber, the operator will be given an all-trunks busy tone. Upon receiving this tone the operator may either release the connector or may wait until such time as an idle sub-office switch and trunk is available whereupon the connection may be established without further operations on the part of the calling operator.

With the foregoing brief description in mind the operations of the various circuits will now be described in detail.

Initiation of a call by a sub-office subscriber

By way of illustration it will be assumed that the subscriber at station T3 initiates a call with the apparatus in normal condition as illustrated. When the receiver is lifted at the calling station, relay 14 operates over a circuit which may be traced from battery, winding of the relay, contacts 19 and 12, line conductor 1, through the loop at the station, line conductor 2, and contacts 11 to ground. Relay 14 closes a circuit for the upper winding of two-step relay 15 by way of contacts 20 and 22. Relay 15 operates in its first step and closes the contacts designated by the Roman numeral I. The other contacts of the relay are not operated at this time. A circuit for the lower winding of the relay is completed at contacts 24 but is ineffective to operate the relay at this time as the winding is short-circuited by the ground applied via contacts 26. Relay 15 also completes a circuit from ground, contacts 26 which do not open, contacts 25 which close, conductor 32, contacts 133, upper contacts of relay 110, winding of relay 103 to battery. Relay 103 operates, completes a locking circuit for itself at contacts 149 and completes an obvious circuit for relay 109. Relay 109 disconnects the battery B from trunk conductor 151 by opening its upper contacts, by closing its lower contacts it connects ground via contacts 137 and conductor 24 to relay 13. Relay 13 operates and at contacts 18, 19, etc. disconnects relay 14 from the various subscribers' lines. Relay 14 opens the original energizing

circuit of relay 15 at contacts 20 and the relay now operates in its second step due to the removal of the short circuit from its lower winding. Relay 15 prepares circuits for relay 16 at contacts 21 and 23 and at contacts 26 opens the original energizing circuit of relay 108. Relay 108 now remains energized over the home contact of the bank which is normally engaged by wiper 118.

Referring now to the repeater (Figs. 3 and 3A) it will be seen that relay 303 which has been energized over a circuit extending from 48-volt battery B1, winding of the relay, upper contacts of relay 302, contacts 316, 345, and 341, trunk conductor 151, upper contacts of relay 109, resistance to 12-volt battery B at the sub-office will deenergize upon the initiation of the call as above-described. Relay 303 completes a circuit from ground, contacts 623 (Fig. 3A), contacts 620, conductor 383, lower contacts of relay 303, contacts 336, conductor 384, lower contacts of relay 605, winding of relay 607 to battery. It may be noted at this point that relays 605, 606, and 607 constitute an impulse-generating relay group. Relay 607 is slightly slow-to-operate due to the slug on its upper, or armature end and operates a short time after a circuit is closed as just described. Relay 607 completes an obvious circuit for relay 606 which energizes slowly due to the resistance shunted across its winding. Relay 606 completes an obvious circuit for relay 605 which operates after a short delay and opens the circuit of relay 607. Relay 607 accordingly releases and opens the circuit of relay 606 and that relay in turn opens the circuit of relay 605. The relays accordingly restore and the latter relay again completes a circuit for relay 607 which re-operates to initiate the second cycle of operation. Relay 607, it may be noted, completes a locking circuit for itself over contact 626 to insure a complete cycle of operation regardless of the condition of the original energizing circuit after the cycle has started. Each time relay 607 energizes an impulse is transmitted from ground on the lower armature of the relay, conductor 387, lower contacts of relay 305, contacts 327 and 322, conductor 368, winding of stepping magnet 401 (Fig. 4) to battery. The magnet accordingly energizes and steps the wipers of switch AS1 ahead to the next set of contacts. As the wipers leave normal position, off-normal contacts 402 close and ground is applied over conductor 363 to operate relay 301. Relay 301 prepares the stopping circuit by closing contacts 317; connects starting conductor 393 to starting conductor 394 by way of contacts 323 and 318; completes a circuit for the upper winding of relay 305 at contacts 319; and completes a second point in the stopping circuit at its lower contacts. Relay 305 which is a two-step relay operates in its first step, closing only its contacts designated by the Roman numeral I to prepare a circuit for its two windings in series. Upon each energization of relay 606 a circuit is completed from battery, resistance 613, contacts 624, trunk conductor 152, thence to the finder-connector at the sub-office, contacts 150 and 129, winding of relay 104 to ground. Relay 104 on each energization completes a circuit from ground at contacts 130, upper contacts of relay 104, winding of relay 103, contacts 123, winding of stepping magnet 113 to battery. The sub-office switch is accordingly advanced step-by-step in synchronism with the switch AS1 at the main office.

The switch continues to step under control of the impulsion relay at the main exchange and

when the wipers engage the contacts in which the calling line terminates, a circuit is completed, from battery, resistance 612 (Fig. 3A) contacts 618, conductor 376, contacts 317, 345, and 341, trunk conductor 151, winding of relay 106, upper contacts of relay 101, wiper 117, line conductor 1, through the loop at the calling station, line conductor 2, wiper 129, lower contacts of relay 101, contacts 128 and 139 to ground. Relay 106 of the selector operates, opens the stepping circuit at contacts 130 and at contacts 131 completes the circuit for relay 105. Relay 105 operates, disconnects relay 105 and ground from the lower trunk conductor by opening contacts 128 and by closing contacts 127 extends the lower side of the calling loop by way of contacts 150, conductor 152, contacts 625, conductor 391, contacts 337, lower contacts of relays 10, lower contacts of relay 301, conductor 329, lower winding of relay 604 to ground. Relay 604 operates in series with relay 106, opens the circuit of impulsion relay 607 at contacts 623 and closes an obvious circuit for relay 603. Relay 603 operates, applies ground to holding conductor 378 at contacts 658, and connects the upper winding of relay 604 to the upper trunk conductor in place of battery through resistance 612 by closing contacts 617 and opening contacts 618. The finder connector and the auxiliary switch AS1 are, therefore, brought to rest on contacts individual to the line on which the call originated. The switch AS1 by means of its wiper 405 connects up a meter associated with this line so that the call may be registered against the calling subscriber. The operation of relay 604 results in the further extension of a connection over the lineswitch LSW to a local first selector of the main exchange, due to the completion of a loop circuit at the lower contacts of relay 604. The two windings of impedance 601 are included in this loop circuit over which the line relay of the lineswitch and the line relay of the first selector operate in the usual manner.

It may be noted that with each step of the magnet of the selector a circuit is closed from the magnet contacts for relay 101 and in parallel therewith by way of contacts 167 and 125, wiper 119, and the release trunk conductors of the various lines for the cut-off relays 1, 2, etc. The relays operate successively although this is without effect until the relay associated with the calling line is operated. Relay 101 operates at each step of the switch and at its upper and lower contacts disconnects the talking wipers of the switch. This prevents interference with the operation of the equipment as the wipers pass over the contacts of lines engaged in other connections. The ground on the test contacts of such lines maintains relay 101 operated when magnet 113 releases between impulses. When relay 103 deenergizes upon the calling line being connected with, the cut-off relay of the calling line is connected over contacts 136 to ground through the lower winding of relay 107. Relay 107 operates, completes a locking circuit for its upper winding at contacts 135, prepares a circuit to relay 110 at contacts 134, applies direct ground to the test wiper 119 at contacts 136, and at contacts 137 opens the circuit of relay 113. Further, starting conductors 32 and 33 are now connected at contacts 132 and starting relay 108, switch FC is disconnected. Any call coming in at this time will, therefore, be assigned to the other selector regardless of the position of the distributor relays as will be apparent later on. Relay 13 now

restores and reconnects relay 14 to the various line conductors so that new calls can be made by sub-office subscribers.

In case a new call should be initiated at this time, relay 14 operates as in the preceding case and relay 15 remains operated over its two windings in series. Relay 14 completes a circuit by way of contacts 20 and 22 for two-step relay 16. Relay 16 operates in its first step, completes a circuit for its upper winding by way of contacts 21 and 27, and at contacts 29 applies ground to starting conductor 33 which extends to the starting relay of the other finder-connector. Relay 16 operates only in its first step at this time, closes the contacts designated by the Roman numeral I and when ground is returned on conductor 34 by the finder-connector, relay 13 will reoperate and disconnect relay 14. Relay 14 removes the short-circuit from the upper winding of relay 16 which thereupon operates in a second step and completes a circuit for relay 17. Relay 17 operates and opens the circuit of relay 15 which restores and in turn opens the circuit of relay 16. Relay 16 restores and prepares the distributor relays for grounding conductor 32 upon the initiation of another call.

When the connection has been established as above described, the terminals assigned to the calling line in the connector banks is marked busy by ground on conductor 368, wiper 404, third contact of the bank engaged by the wiper, conductor 417, lower winding of relay 552 to battery. Relay 552 operates and at contacts 560 connects ground to test contact 567.

Dialling

The general operation resulting from dialling the digits of a called number will now be described. As previously stated, the sub-office is identified by the digits 2, 4, 5, 1 and a particular line of the sub-office is selected by an additional digit which follows the four identifying digits. Main office lines are identified by five digit numbers of which one or more of the first four digits differ from the corresponding digit or digits of sub-office numbers. The subscriber dials a digit of a wanted number, interrupting the circuit of line relay 604 of repeater R and that relay responds. When relay 604 restores a circuit is closed from ground, contacts 623, 619, lower winding of relay 602, conductor 386, contacts 356, conductor 381, winding of magnet 531 of auxiliary switch AS3 to battery. The magnet advances the wipers 503—506 one step for each impulse transmitted by the impulse relay. The loop circuit over line switch LWS to the first selector is interrupted at the lower contacts of relay 604 and the first selector is stepped to the level indicated by the digit dialled. Relay 602 operates in response to the first impulse, short circuits its upper winding, completes a circuit for relay 315 at contacts 616, removes the high resistance upper winding in impedance 601 from the loop circuit to the switch ahead at contacts 614 and connects the low resistance winding in this circuit at contacts 615. At its lower contacts, relay 602 opens the circuit to wiper 506 of switch AS3. The operation of relay 315 is without effect until the final digit of a sub-office number is dialled. Shortly after the last impulse of the series, relay 602 restores and completes a circuit over wiper 506 of switch AS3, the effect of which will depend upon the value of the digit dialled as will be explained subsequently.

First digit

In case the first digit dialled is the digit 1, the wipers of switch AS3 come to rest on the first contacts of the bank and upon the release of relay 602 a circuit is closed from ground, contacts 621, lower contacts of relay 602, conductor 514, wiper 506, first bank contact, conductor 519, contacts 669, to conductor 377; for the digits 3 and 6—0 the ground on wiper 506 is applied directly to conductor 377; for the digit 4, ground is applied over conductor 521 and contacts 653 to conductor 377; and for the digit 5 ground is applied over conductor 520 and contacts 646 to conductor 377. These digits indicate that the called subscriber's line is outside of the sub-office. The ground on conductor 377 operates relay 314 which locks the ground on conductor 378, prepares the busy tone circuit at contacts 352, disconnects the stepping magnet of the switch AS3 at contacts 356 and at contacts 355 connects battery through a resistance to relay 602. The switch AS3 accordingly remains in its operated position throughout the remainder of the call as it will receive no more impulses and its restoring circuit is opened at contacts 622. The further extension of the call will be described in later paragraphs.

In case the first digit dialled is the digit 2 indicating that the line called may be a sub-office line, ground is applied over wiper 506, conductor 522, contacts 651, winding of relay 611, resistance 662 to battery. The first step of the switch wipers also results in the closure of the circuit from ground, resistance 528, wiper 503, conductor 518, contacts 656, resistance 652 to battery. Relay 611 is, therefore, partially short-circuited by the ground through resistance 528. When the circuit is completed over wiper 506, relay 611 operates in its first step, closing only the contacts designated by the Roman numeral I. The normally closed contacts are not opened at this time. The closing of the lower contacts of the relay results in the completion of the circuit from ground, contacts 657, conductor 515, off-normal contacts 502, interrupter contacts of magnet 501, winding of the magnet to battery. The magnet accordingly operates in its self-interrupting circuit until the wipers are in normal position whereupon contacts 502 open and stop the stepping action. With the wipers in normal position the shunt is removed from relay 611 and that relay now operates in its second step over an obvious circuit including its upper contacts to ground on conductor 378. Relay 611 disconnects itself from conductor 522 at contacts 651 and at contacts 652 connects this conductor to conductor 377 so that a subsequent digit 2 will bring about the energization of relay 314. Conductor 521 is disconnected from conductor 377, at contact 653 and at contacts 654 is connected by way of contacts 644 to relay 610, so that the second digit if it is the digit 4 will operate relay 610 instead of relay 314 as was the case with a first digit 4. The circuit over which the shunt was applied to relay 611 is transferred to relay 610 by way of contacts 655 and 649. The homing circuit for the switch AS3 which was completed over the lower contacts of relay 611 as previously stated, is opened at contacts 657. The removal of ground from conductor 515, now permits switch AS3 to operate and release under control of relay 610.

Second digit

Relay 604 responds to the second digit in the 75

same manner as for the first digit, transmits impulses to the stepping magnet of the switch AS3 and interrupts the loop to the main office switches as before. If the second digit dialled is any other than the digit 4, ground will be applied over wiper 506 and the circuits previously traced to conductor 377 to operate relay 314 and prevent further operation of the switch AS3. If the second digit is the digit 4, which is the second digit of sub-office numbers, a circuit will be closed over wiper 506, conductor 521, contacts 654 and 644 winding of relay 610, resistance 661 to battery. Relay 610 is partially shunted by ground applied over wiper 503 and at this time operates in its first step to close the contacts designated by the Roman numeral I. The restoring circuit of switch AS3 is closed by way of contacts 650 and the lower contacts of the relay and the switch wipers are restored to normal position as in the previous instance. Upon the removal of the shunt from relay 610, the relay operates in its second step transferring conductor 521 from its connection to the relay to connection with conductor 377 at contacts 645, so that a subsequent digit 4 will operate relay 314. Conductor 650 is disconnected from conductor 377 at contacts 646 and connected by way of contacts 647 and 638 to relay 609. The circuit over which relay 610 was partially shunted is transferred by way of contacts 648 and 642 to relay 609.

Third digit

In case the third digit is any other than the digit 5 ground is applied over wiper 506 to conductor 377 to bring about the operation of relay 314. The connection will then be extended over the main office switches in the usual way. In case the digit 5 is dialled, ground is applied over wiper 506, conductor 520, contacts 647 and 638, winding of relay 609, resistance 660 to battery. Relay 660 is partially shunted by ground through resistance 528 and operates in its first step at this time, closing the contacts designated by the Roman numeral I. Relay 609 in addition to preparing a circuit for operating in its second step completes the restoring circuit for switch AS3 by way of contacts 643 and the lower contacts of the relay. Switch AS3 returns to normal position as in the previous instances and the shunt is removed from relay 609. Relay 609 then operates in its second step, disconnects itself from conductor 620 at contacts 638 and connects this conductor through to conductor 377 at contacts 637 so that a fourth digit 5 will operate relay 314. Conductor 519 is disconnected from conductor 377 at contacts 640 and connected by way of contacts 639 and 631 to relay 608. The circuit for shunting relay 609 is transferred to relay 608 by way of contacts 641 and 632.

Fourth digit

If the fourth digit is of any other value than 1, ground will be applied over wiper 506 to conductor 377 to operate relay 314. The connection will then be extended over the main office switch train.

In case the fourth digit is the digit 1, ground is applied over wiper 506, conductor 519, contacts 639 and 631, winding of relay 608, resistance 659 to battery. Relay 608 is shunted by the ground through resistance 528 and operates in its first step at this time closing the contacts designated by the Roman numeral I. These contacts complete the usual operating circuit for the relay and the restoring circuit for switch AS3. Upon the restoration of the auxiliary switch to normal

position the shunt is removed from relay 608 and that relay operates in its second step, disconnects conductor 519 from the relay and connects it by way of contacts 630 to conductor 377. Conductor 375 is connected by way of contacts 629 to conductor 524 for purposes to be explained subsequently. The loop circuit for the main exchange switch train is opened at contacts 627 and the lower contacts of relay 608. A busy-tone circuit is prepared at contacts 628.

Test for idle sub-office revertive connector

Proceeding with the description of the connection it will be assumed that the calling subscriber has dialled the digits 2, 4, 5, 1 which indicate that the called subscriber is located in the sub-office. The test for an idle revertive connector switch is made upon the return of auxiliary switch AS3 to normal. Wiper 504 engages its home contact which is connected by way of conductor 396' to repeater 2R. In case a local call in the sub-office is in progress on the second repeater at this time, ground will be applied to conductor 396' in a manner to be explained subsequently. This ground by way of wiper 504, conductor 524, contacts 629, conductor 375, contacts 357 and 354, winding of relay 313 to battery energizes relay 314. Relay 314 on operating opens the impulsing circuit for switch AS3 and prepares the busy-tone circuit as in the previous instances.

The calling subscriber may dial the final digit of the number although this would be without effect since the circuit for stepping magnet 501 is open at contacts 356 and the loop circuit of the main office switch train is open at the upper and lower contacts of relay 608. A busy tone will now be returned to the calling subscriber by way of the conductor designated busy, contacts 352, upper contacts of relay 311, conductor 374, contacts 628 and 614, conductor 373, through the talking condenser, contacts 331 through conductor 151 and thence through the calling subscriber's loop and back to ground through the lower winding of relay 604. The tone will inform the calling subscriber that the connection cannot be established at this time and he is expected to hang up and release the connection as will be explained subsequently.

Idle revertive connector available

In case there is no other call in the sub-exchange in progress following the dialling of the fourth digit as above described, wiper 504 of switch AS3 will find no ground on its home contact and relay 314 is not energized. The calling subscriber then dials the final digit of the called number which for convenience may be assumed to be the digit 7. Relay 604 will respond in the usual way and transmit a series of seven impulses over the previously traced circuit to stepping magnet 501 of switch AS3. The wipers of the switch are stepped to the seventh set of contacts which correspond to the wanted line.

Called line busy

The called line is tested for its busy or idle condition prior to the release of relays 602 and 315 which remain operated a short interval after the last impulse of the series is received. The test circuit may be traced from conductor 415, seventh contact of the bank engaged by wiper 504, conductor 524, contacts 629, conductor 375, contacts 379, winding of relay 313 to battery. If the called line is engaged in an incoming or out-

going call the associated line relay in this case relay 553 will be operated and contacts 555 will be closed by applying ground to conductor 415. This ground, of course, will be applied over the 5 wiper 404 of the auxiliary switch 2AS1 associated with the second repeater. Relay 313 accordingly operates, opens the circuit of relay 311 and prepares a locking circuit for itself. When relays 602 and 315 restore, the circuit for initially operating relay 315 is transferred by way of contacts 357 and 354 to relay 314 which operates. Relay 314 completes the busy tone circuit at contacts 352 and the busy tone is returned to the calling subscriber exactly as in the preceding instance.

Called line idle

In case the called line is idle wiper 504 of switch AS3 will find no ground on the test contact and relay 313 does not operate. Upon the 20 release of relay 602, a circuit is closed by way of contacts 621, lower contacts of relay 602, conductor 514, wiper 506, seventh contact of the bank engaged by this wiper, conductor 377, winding of relay 314 to battery. Relay 314 operates, prepares the busy-tone circuit, and opens the impulsive circuit as in the previous instance. A circuit is now completed for relay 311 from ground at contacts 633, conductor 382, winding 25 of the relay, upper contacts of the relay 313, contacts 353 and 357, conductor 375, contacts 629, conductor 524, wiper 503, seventh contact of the bank engaged by the wiper, conductor 415, lower winding of relay 553 to battery. Both relays 311 and 553 operate in this circuit. The latter relay 30 opens the starting circuit at contacts 564, and applies ground to the test contact 570 in the connector banks at contacts 565. Relay 311 on operating 35 opens the busy-tone circuit, at its upper contacts, completes an obvious circuit for relay 310, and at contacts 397 applies ground by way of conductor 396 to the home contact of the bank engaged by wiper 504' of the auxiliary switch 2AS3 associated with repeater 2R. This auxiliary switch corresponds to switch AS3 associated with repeater R and the wiper 504' corresponds to wiper 504. It will be apparent that an attempt 40 to establish a call between subscribers in the sub-office over the other trunk and repeater 2R will result in the calling subscriber receiving the busy indication as was described previously. As a further result of the operation of relay 311 a marking ground is applied by way of contacts 397, lower contacts of relay 306, conductor 388, wiper 505, seventh contact in the bank engaged by this wiper, conductor 414 to the seventh contact in the bank of switch AS2. This ground 45 serves to mark the calling line for purposes which will be apparent as the description proceeds. As a result of the operation of relay 310 a holding circuit is completed for relay 604 extending from ground, upper contacts of relay 312, upper contacts of relay 310, contacts 317, conductor 376, contacts 617, upper winding of relay 604 to battery. Trunk conductor 151 is disconnected from the upper winding of relay 604 at contacts 345 and extended by way of contacts 346 to the upper winding of relay 308. Trunk conductor 152, which as previously explained was 50 connected to the lower winding of relay 604 is now opened at the lower contacts of relay 310.

Referring now to the switch FC in the sub-office it will be recalled that relay 106 has been maintained in its operated position in series with 55 relay 604 of the repeater at the main office. Upon

the disconnection of the latter relay as explained above, relay 106 will release, thereby extending the lower talking conductor of the switch by way of contacts 128 and 138 through the winding of high resistance relay 111 to ground. It will be 5 recalled that battery through relay 308 is connected to conductor 151 at the main office and this battery by way of the winding of relay 106, upper contacts of relay 101, wiper 117, over the loop circuit of the calling line, back over wiper 120, 10 lower contacts of relay 101 and the lower talking conductor of the switch operates relay 111. Relay 308 also operates in series with relay 111 but due to the high resistance of the latter relay, relay 106 does not operate. Relay 308 completes 15 a new holding circuit for the upper winding of relay 604 at its upper contacts, and completes a new circuit for impulse generating relay 607 by connecting ground to conductor 388 at contacts 338. The impulse relays 605, 606, and 607 operate 20 to transmit impulses in exactly the same manner as when the connection was being established, as was described in detail in preceding paragraphs. The impulses generated at this time, however, operate different switches than in the preceding case. Since relay 608 was operated after the dialling of the fourth digit, a circuit is closed for relay 302 by way of contacts 636 and conductor 386 and relay 302 is energized. The impulses generated at the lower contacts of relay 30 202 are, therefore, applied over conductor 387, lower contacts of relay 305, contacts 327 and 321, conductor 367, winding of magnet 407 of switch AS2 to battery. The wipers of this switch are accordingly advanced step-by-step until the called 30 line is reached. Impulses are also transmitted from battery through resistance 613, contacts 624, conductor 152, contacts 149, conductor 155, off-normal contacts 209 (Fig. 2), winding of relay 202 to ground. Relay 202 operates in response to 40 each of these impulses and transmits an impulse by way of the stepping magnet interrupter contacts, winding of the magnet, to battery. The stepping magnet on operating opens its interrupter contacts and slow-releasing relay 201 is 45 thereupon connected in series with the magnet. Relay 201 operates and completes a new circuit for relay 202 independent of off-normal contacts 209. The wipers of the switch are advanced one 50 step whereupon the off-normal contacts open. Subsequent impulses are transmitted to relay 202 by way of contacts 214. Relay 201 remains operated throughout the series of impulses and in addition to maintaining the impulsive circuit, opens the test circuit of its upper contacts. It 55 should be noted at this time that relay 111 on operating as previously described completed a circuit by way of contacts 148, conductor 154, winding of relay 204 to battery. Relay 204 on operating connects the upper winding of relay 205 to the test wiper at its upper contacts, opens the restoring circuit of the switch at contacts 215, and prepares the ring-cut-off circuit at contacts 217. Switch RC at the sub-office and auxiliary switch 60 AS2 at the main office are stepped in synchronism until the wipers of both switches reach their seventh set of contacts which correspond to the called line which was marked responsive to the digit dialled by the calling subscriber. When 70 wipers of the switch AS2 engage their seventh set of contacts, a circuit is closed from ground at contacts 397, lower contacts of relay 306, conductor 388, wiper 505 of switch AS3 which is standing on the seventh set of contacts of its 75

bank, conductor 414, seventh contact of the bank engaged by wiper 411, said wiper, conductor 365, contacts 335, winding of relay 306 to battery. Relay 306 operates, opens the circuit of the impulse generating relay at contacts 330 to prevent further impulsing, completes a locking circuit for itself by way of contacts 328, conductor 364, wiper 410, seventh contact of the bank engaged by that wiper, conductor 415, seventh contact of the bank engaged by wiper 504, conductor 524, contacts 629, conductor 375, contacts 357, 353, upper contacts of relay 313, winding of relay 311, conductor 382 to ground at contacts 683. Relay 306 also completes a circuit for relay 307, prepares the ringing circuit at contacts 329 and disconnects ground from conductor 388. At the sub-office relay 202 remains normal after the cessation of impulses and relay 201 restores after a slight delay. A circuit is now completed from battery through the winding of cut-off relay 8 associated with the called line T7, conductor 6, wiper 211 which is engaging the seventh contact of its bank, upper contacts of relays 201 and 204, upper winding of relay 205 to ground. Relay 205 operates, closes points in the talking circuit of its upper and lower contacts, applies direct ground to the test wiper at contacts 219, completes an obvious locking circuit for its lower winding over conductor 153, and completes the ringing circuit at contacts 220. Ringing current is now sent out to the called line from the generator lead GEN, lower winding of relay 309, contacts 329, lower winding of relay 308 and condenser 395 in parallel, contacts 346, and 341, trunk conductor 151, upper contacts of relay 205 of switch RC, wiper 210, line conductor 4, through the bell and condenser at the called station, line conductor 5, wiper 213, lower winding of relay 203 and the condenser in parallel, contacts 217, 220, 222, and 227 to ground. The bell at the called substation rings intermittently to notify the subscriber of the call. A small quantity of the ringing current is transmitted to the calling line by way of conductor 151, winding of relay 106 and the condenser in parallel, upper contacts of relay 101, wiper 117 over the loop of the calling line, wiper 120, lower contacts of relay 101, contacts 128 and 138, winding of high resistance relay 111 to ground. The amount of ringing current flowing in this circuit is relatively small due to the very high resistance in relay 111. Further, the resistance to this relay is so great that relay 309 is prevented from operating over the direct current path afforded therethrough. When the called subscriber answers a direct current bridge is closed over the calling line and a low resistance path is completed for relays 203 and 309 and these relays accordingly operate. Relay 309 opens the ringing circuit at contacts 241, and extends trunk conductor 151 through to the upper winding of relay 604 and battery by way of contacts 343. Relay 309 also completes a locking circuit for its upper winding at contacts 344 and closes a further point of the talking circuit at its lower contacts. Relay 203 completes a locking circuit for its upper winding at contacts 215, and at its upper contacts connects ground by way of conductor 156 and the lower contacts of the relay 111 to the lower talking conductor of the switch FC. Relay 111 is shunted by this direct ground and restores, and relay 106 now operates and completes the circuit for relay 105. Relay 105 operates and connects the lower talking conductors of the switch through to trunk conductor 152 by way of contacts 150. The release

of relay 111 removes ground from conductor 154 and relay 204 of switch RC restores to complete the talking circuit. Relay 308 of repeater R releases responsive to the operation of relay 309, and trunk conductor 152 is thereby connected by way of contacts 625, conductor 391, contacts 326, lower contacts of relays 309 and 301, conductor 389, lower winding of relay 604 to ground. Both subscribers are now connected to trunk conductors 151 and 152. Talking battery and ground are supplied through the windings of line relay 604.

Release after a completed connection

At the termination of a connection as above described both parties will restore their receivers, thereby opening the direct current loops at their respective stations. Relay 604 of repeater R accordingly restores and opens the circuit of relay 603. Relay 603 on restoring removes ground from holding conductor 378 thereby permitting relays 309, 312, 314, and 608-611 to restore. A circuit is again closed for the impulse generating relay group comprising relays 605-607 and these relays operate as in the preceding instances to transmit ground and battery impulses. Relays 301 and 302 of the repeater remain energized over circuits including the off-normal contacts of auxiliary switches AS1 and AS2, respectively. Relay 303 remains in normal position and relay 305 remains operated in its first step with the contacts designated by the Roman numeral I closed. Impulses are all transmitted from ground at the lower contacts of relay 607, conductor 387, lower contacts of relay 305, contacts 327 and 321, conductor 367, winding of magnet 407 to battery. Magnet 407 operates and advances the wipers of switch AS2 step-by-step until the home position is reached whereupon off-normal contacts 408 open and permit relay 302 to restore. Relay 302 transfers the impulsing circuit by way of contacts 322 and conductor 368 to magnet 401 of switch AS1. This switch is then advanced step-by-step until the wipers return to normal position, whereupon off-normal contacts 402 open and permit relay 301 to restore. Relay 301 reconnects relay 302 to the upper trunk conductor and disconnects ground from the upper winding of relay 305 and from relay 307. Relay 307 restores. Relay 305 now operates in its second step over a circuit including a contact of relay 303 which has not been re-operated unless the sub-office switches have reached normal position. Relay 305 remains operated while the sub-office switches are returning to normal position and maintains the stepping circuits of the auxiliary switches open at its lower contacts.

In the sub-office, relay 106 releases responsive to the calling subscriber hanging up and opens the circuit of relay 105. Relay 105 restores and connects relay 104 direct to the lower trunk conductor. The impulse relay group at the main exchange transmits battery impulses over trunk conductor 152 in the same manner as for the original setting of the switches FC and RC. Relay 104 responds and transmits a ground impulse through the winding of relay 103 to battery through resistance 116. Relay 103 operates in response to the first impulse and again shorts circuits the upper winding of relay 103, thereby causing that relay to release from its second step and connect stepping magnet 113 in series with relay 103. Subsequent impulses operate the magnet 113 to restore the switch wipers to nor-

mal position. Relay 103 remains operated throughout the series of impulses and at its upper contacts prepares a circuit for relay 110. As soon as relay 102 releases the locking circuit 5 for the upper winding of relay 107 is opened at the upper contacts of relay 102 and that relay releases. Before this release occurs, however, relay 110 operates and locks by way of contacts 145 and the upper contacts of relay 108 to ground 10 at the upper contacts of relay 105. Relay 110 prepares a circuit for relay 112 at contacts 144, and at contacts 146 completes a circuit for relay 101. Relay 101 operates and opens the talking conductors of the switch during the release of the wipers. 15 When the wipers reach normal or home position the holding circuit of relay 109 is opened due to wiper 119 leaving the last contact of the bank relay and 109 restores. Battery is connected to trunk conductor 151 at the upper contacts of relay 109 and energizes relay 303 which has been 20 reconnected to the trunk, assuming that the auxiliary switches at the main office have been restored to normal as above described. Relay 303 opens the holding circuit of relay 305 which 25 releases. Relay 303 stops the operation of the impulse generating relays by opening its lower contacts and relay 305 restores the local impulsing circuit to normal. At the sub-office relay 104 no longer receives impulses and relay 103 releases after a short interval. The circuits of 30 relays 102 and 110 are opened and these relays restore.

Referring now to revertive connector RC, the release of relay 102 of switch FC as above described removes ground from conductor 153 thereby permitting relay 205 of the switch RC to release. Relay 204 having previously released upon the restoration of relay 111, relay 205 now completes the restoring circuit of the switch by 35 closing contacts 221. This restoring circuit includes contacts 221, 222, 221, and 216, off-normal contacts engaged by wiper 212, and the interrupter contacts of the stepping magnet. The magnet operates in its self-interrupting circuit to 40 restore the switch to normal position, whereupon the impulsive circuit is opened by wiper 212 leaving the last bank contact and relay 202 is again connected to the control conductor 155 by closure of off-normal contact 209.

50 Auxiliary switch AS3 at the main office returns to normal upon the release of relay 603 which completes a circuit by way of contacts 622, conductor 515, off-normal contacts 502, interrupter contacts of the magnet, winding of the magnet to battery. When the wipers reach normal position, the restoring circuit is opened at the off-normal contacts. All switches have now returned to normal and the apparatus is in condition to respond to the next call.

60 *Release after attempted local call with reverting call switch busy*

Release in this case is substantially the same as that for a completed call. The calling subscriber on hanging up releases relays 604 and 603 and counting relays 608-611 also restore. The starting circuit for the impulse generating relay group is completed by relays 604 and 603 65 and these relays transmit impulses to restore auxiliary switch AS1 and the sub-office switch FC to normal. Since the final digit has not been dialled, auxiliary switches AS2 or AS3 have not been operated and consequently there is no necessity of restoring them. Upon the return of the

sub-office switch to normal, battery is re-applied to the upper trunk conductor and relay 303 operates to stop the impulse generating relays and to permit the equipment to assume its normal position. 75

Release after attempted call to a busy line

The release in this case is the same as that for the preceding case, except that switch AS3 will have been operated to the contacts of the called 10 line. Upon the release of relays 604 and 603 the usual restoring circuit will be completed for the stepping magnet 501 of the switch AS3. Switch AS1 and the sub-office selector switch S will be returned to normal under control of 15 the impulse generating relay in the usual manner.

The release after a connection of this type is exactly the same as that for an attempted connection to a busy sub-office line, except that in this case not more than three of the counting 20 relays will be operated. These relays, of course, restore in the usual way upon the release of relay 603 which removes ground from holding conductor 378. Relay 604 opens the loop to the main office switch train and these switches release in the usual manner. 25

Incoming call to a sub-office subscriber

The operations involved in establishing a connection to a sub-office subscriber from a sub- 30 subscriber in the main office will now be described. The calling party will dial the number assigned to a wanted sub-office line which for convenience will be assumed to be the number 24517 assigned to sub-office line T7. The dialled digits will 35 operate the automatic switches at the main office in the usual manner and a connector will set its wipers on contacts 570-572 which are assigned to the wanted sub-office line. The connector will test the line in the usual manner, that is by 40 applying ground through the low resistance winding of the switching relay to the test wiper. This ground by way of contact 570, upper winding of relay 553, contacts 564, resistance 574, conductor 393, contacts 324, winding of relay 304 to battery will energize relay 304. Relay 553 and the switching relay of the connector do not energize at this time due to resistance 574 and to the relatively high resistance of relay 304 which 45 cuts down the current flow in the circuit. Relay 50 304 on operating completes a circuit for the impulse generating relays at contacts 325 and at contacts 326 connects impulsive conductor 387 to the motor magnet of auxiliary switch AS2. The ground applied to the test contact of the 55 connector bank will be extended in a parallel circuit by way of contacts 574 and 550, and conductor 414 to the seventh contact of the bank engaged by wiper 411 of auxiliary switch AS2. This will mark the wanted sub-office line and 60 determine the number of impulses to be transmitted to the finder connector at the sub-office.

The impulse generating relays transmit impulses to the auxiliary switch AS2 in the usual manner advancing the wipers of this switch step-by-step. Impulses will be transmitted simultaneously over a circuit from battery, resistance 613, contacts 624, trunk conductor 152, contacts 150 and 129, winding of relay 104 to ground. Relay 104 responds, transmits a series of impulses 65 through relay 103 to stepping magnet 113 of the switch FC. Relay 103 remains operated during the series of impulses and completes a circuit for relay 110 which also operates. Relay 110 disconnects starting relay 108 from the incoming 70 75

starting conductor, completes a circuit for relay 112 at contacts 144 which is effective at this time since relay 109 is unoperated and completes the circuit for relay 101. Relay 101 operates and 5 opens the talking conductors of the switch so that there will be no testing of the calling lines passed over during the operation of the switch. Relay 112 operates, prepares a locking circuit for itself to holding conductor 153, and prepares a point in the ringing circuit at its lower contacts. 10

After seven impulses have been transmitted by the impulse generating relays, the wipers of the switch FC will engage the contacts associated with the called line and the wipers of auxiliary switch AS2 will be in a similar position. When 15 wiper 411 encounters the ground on the seventh contact of its bank, a circuit is completed over conductor 365, contact 335, winding of relay 306 to battery. Relay 306 operates, opens the 20 circuit of the impulse generating relays at contacts 330 and completes a circuit for relay 307 at its upper contacts. The stepping of switch AS2 from its normal position results in the closure of off-normal contacts 408 and ground 25 over conductor 366, energizes relay 302. Relay 302 disconnects starting relay 303 from the upper trunk conductor and completes a holding circuit for relay 307. Relay 306 has a relatively low 30 resistance and permits relay 553 and the switching relay of the connector to operate at this time. The switching relay of the connector completes the usual ringing circuit over the talking wipers of the connector and relay 553 locks over its lower winding to ground on the test contact. 35 This ground is also extended by way of conductor 415, wiper 410 of auxiliary switch AS2, conductor 364, contacts 328 to hold relay 308 operated. In the sub-office, relay 109 operates 40 as soon as the wipers of the switch leave their home position. The normal battery connection to conductor 151 is opened at the upper contacts of the relay, ground is applied to holding conductor 153 at contacts 141, and a circuit is completed for relay 13 at the lower contacts of the 45 relay to prevent the starting apparatus from functioning in case a call should originate in the sub-office at this time. As soon as the wipers of the switch engage the contacts associated with the called line, cut-off relay 8 of the called line 50 operates in series with the lower winding of relay 107. Relay 107 operates and locks to holding conductor 153 and transfers the incoming starting conductor 32 of the second finder-connector switch at the sub-office by way of outgoing starting conductor 33 and contacts 132. 55

A connection has now been established with the called line and ringing current is transmitted by the connector in the usual manner. The circuit for this ringing current may be traced from the 60 upper talking wiper of the connector, contact 571, conductor 420, wiper 409 of auxiliary switch AS2, conductor 361, contacts 332, trunk conductor 151, winding of relay 106 and the condenser in parallel, upper contacts of relay 101 which restores at 65 the end of the impulsing, wiper 117, line conductor 4 through the bell and condenser at the called station, line conductor 5, wiper 120, lower contacts of relay 101, contacts 128 and 138, lower contacts of relay 112 to ground. Neither relay 70 106 nor the ring-cut-off relay of the connector operate at this time as no direct current flows over the circuit. The bell at the called station rings intermittently to advise the subscriber of the incoming call. When the subscriber answers 75 the call a direct current bridge is closed at the

called station which permits relay 106 and the ring-cut-off relay of the connector to operate. The ring-cut-off relay of the connector stops the ringing and connects up the battery feed relay in the usual manner. Relay 106 completes an 5 obvious circuit for relay 105 which operates and connects the lower talking conductor of the switch FC through to trunk conductor 152 by way of contacts 127 and 150. Conductor 152 is connected by way of contacts 625, conductor 391, 10 contacts 336 and 340, conductor 369, wiper 412 of switch AS2, seventh bank contact, and conductor 421 to the bank contact 572 which is engaged by the lower talking wiper of the connector. The talking battery for the called subscriber is fed through the back-bridge relay of the connector in the usual manner and the calling and called subscriber may converse over the circuit above traced. 15

Release

20

The release of the connection is brought about by both subscribers hanging up. The calling subscriber in hanging up first will release the line relay of the connector but the back-bridge 25 relay is energized over the called subscriber's loop and will prevent the switch from releasing at this time. When the called subscriber hangs up, the back-bridge relay of the connector releases and permits the switch to restore in the 30 usual manner. Relay 106 releases and opens the circuit of relay 105. The removal of ground from the test contact of the connector bank permits relays 553 and 306 to restore. Relay 302 is held up over the off-normal contacts of switch AS2. 35 Relay 303 will be in normal position and the release of relay 306 will complete a circuit at contacts 330 for the impulse generating relays. These relays transmit impulses in the usual manner to restore switch FC at the sub-office and 40 auxiliary switch AS2 at the main office. The circuit for restoring switch AS2 is the same as that over which the switch was initially set. The circuit for restoring switch FC is also the same as that over which it was previously set. In this 45 case, however, the first impulse serves to restore relay 102 far enough to close contacts 123 and open its upper contacts. When the switch AS2 reaches its normal position, off-normal contacts 608 open and the relay 302 restores and reconnects relay 303 to the trunk conductor 151. In case the sub-office switch has not yet reached 50 normal position relay 303 will be normal and upon the release of relay 302, relay 305 will operate in its second step and open the impulsing circuit for switch AS2 at its lower contacts. The impulses will continue to go out to the sub-office until switch FC reaches normal position. Upon the sub-office switch reaching normal position, wiper 118 opens the circuit of relay 109 and that 60 relay restores and applies battery to trunk conductor 151 to operate relay 303. Relay 303 on operating opens the impulsing circuit at its lower contacts and opens the circuit of relay 305 which restores. The release of relay 109 removes 65 ground from holding conductor 153 and relay 112 to restore. All of the apparatus has now returned to normal condition and is ready for the next call. 75

Incoming call with all trunks busy

70

It will be recalled that a starting circuit for repeater R was completed over conductor 393 when the repeater was idle at the time a connection was extended. In case this repeater is in 75

use when the call arrives, the second repeater, if not in use will be started, as conductor 393 is connected by way of contacts 318 or 333 to outgoing starting conductor 394 which goes to repeater 2R. Conductor 394 corresponds to conductor 393 of repeater R as far as connections in repeater 2R are concerned. A relay in repeater 2R corresponding to relay 304 of repeater R will operate in response to the incoming call provided the repeater is idle at this time and the connection will be completed over the second trunk exactly as was described for the connection over the first trunk.

If the second trunk should also be busy when the call arrives, starting conductor 394 will be connected to conductor 394' instead of to the starting relay. This conductor instead of going to the starting relay of a third repeater is, in the instant case, connected to all-trunks busy relay 556. Relay 556 and the busy test relay of the connector operate in series. The connector returns busy tone to the calling subscriber in the usual way and he is expected to release the connection and call later. Relay 556 has special functions to perform in toll calls and its operation will be described hereinafter.

Toll offering

Since the present system may be used in systems provided with a toll switch train equipped for so-called toll offering service it is, of course, necessary to make provisions for the extension of toll calls to sub-office lines busy in local connections. In case the line is busy in a local connection with another subscriber in the sub-office the connector terminal will be grounded to give the busy indication and switches AS1 and AS2 will be engaged with contacts corresponding to the calling and called lines, respectively. When a calling operator now extends a connection to one of the lines engaged in this connection over the usual toll switch train, the connector will return the usual busy supervision to notify the operator of the condition of the line. The operator may now cause the connector to cut in on the line and establish a temporary talking connection. This talking connection will extend over the upper talking wiper of the connector, conductor 418, wiper 409 of switch AS2, conductor 361, contacts 332 to upper trunk conductor 151, or over conductor 418, wiper 403 of switch AS1, conductor 360, upper contacts of relay 314 to trunk conductor 151. A circuit also extends from the lower talking wiper of the connector, conductor 419, wiper 412 of switch AS2, conductor 369, contacts 340 and 336, conductor 391, contacts 625 to trunk conductor 152, or over conductor 419, wiper 406 of switch AS1, conductor 370, and lower contacts of relay 314 to trunk conductor 152. Both the calling and called subscribers are connected to the trunk, the calling operator can obviously converse with them and offer the toll call. Should the call be accepted the unwanted party may withdraw from the connection and the toll call can be established over the path just described.

A toll offering connection can be completed as above described even though both sub-office trunks are busy as long as the called line itself is engaged in a connection. If the called line is idle, however, and both sub-office trunks are busy as long as the called line itself is engaged in a connection. If the called line is idle, however, and both sub-office trunks are busy, the connection cannot be established and the toll operator is given an all trunks busy tone when she at-

tempts to offer the call. When the connector engages the contacts associated with the wanted line, for example line T7, the test circuit of the connector is extended over bank contact 570, upper winding of relay 553, contacts 564, resistance 574, conductor 393, and the chained starting circuit to the two repeaters which, as previously described, now returns on conductor 394' from repeater R2, winding of relay 556 to ground. Relay 556 operates in series with the busy test relay 10 of the connector, completes a holding circuit for itself by connecting battery through resistance 517 to conductor 393 at contacts 523, and connects all-trunks busy tone to the talking conductors associated with the various line contact sets 15 on all lines which are not engaged in other connections. The busy test relay of the connector returns the usual busy tone to the operator. In case the operator attempts to set up an offering connection the busy tone is disconnected in the 20 connector and a temporary connection is set up over the talking wipers of the switch. A circuit then extends over the upper talking wiper of the connector, contact 571, conductor 420, contacts 563 and 566, through the condenser to the all- 25 trunks busy tone generator. This tone, which will ordinarily be different from the usual busy tone, notifies the operator that the connection cannot be completed due to all trunks to the sub-office being busy. The operator may wait until 30 such time as a trunk is available or release the connection. If she elects to wait, when a trunk becomes idle the chain circuit will be opened in the repeater associated with the now idle trunk and relay 556 will restore and remove the all- 35 trunks busy tone from the line. The chain circuit will be connected through to the starting relay and the repeater and the apparatus will then operate as previously described for an incoming call to an idle line and the connection will be 40 completed in the usual manner.

What is claimed is:

1. In a telephone system, two offices connected by a trunk line, two switches associated with the trunk line at one office, a registering device associated with the trunk line at the other office, a calling line and a called line at said one office, means including one of said switches for extending the calling line to said registering device via said trunk line, means controlled over the calling line for registering the number of the called line in said device, and means controlled by said device for operating the other of said switches in accordance with the number registered to extend a connection to the called line. 55

2. In a telephone system, two offices connected by a trunk line, two switches associated with the trunk line at one office, a registering device associated with the trunk line at the other office, a calling line and a called line at said one office, means including one of said switches for extending the calling line to said registering device via said trunk line, means controlled over the calling line for registering the number of the called line in said device, means controlled by said device for operating the other of said switches in accordance with the number registered to extend a connection to the called line, and means associated with said device for transmitting signaling current over the trunk line to signal the 70 called line. 65

3. In a telephone system, two offices connected by a trunk line, two switches associated with the trunk line at one office, a registering device associated with the trunk line at the other office, a 75

- calling line and a called line at said one office, means including one of said switches for extending the calling line to said device via the trunk line, means controlled by the calling party for 5 setting said device in accordance with the number of the called line, means controlled by said device for operating the other of said switches to extend the connection to the called line, and means for supplying talking current to both 10 parties to the connection over the trunk line.
4. A telephone system as claimed in claim 2 in which part of the signalling current transmitted over the trunk line to signal the called line is permitted to flow over the calling line to inform 15 the calling party that the called line is being signalled.
5. In a telephone system, two offices connected by a trunk line, a switch associated with the trunk line at each office, subscribers' lines accessible to 20 the switch at one office, call registers individual to said lines accessible to the switch at the other office, and means responsive to the initiation of a call on one of said lines for simultaneously operating said switches to connect with the calling line 25 and the call register associated with that line, respectively.
6. In a telephone system, two offices connected by a trunk line, a switch associated with the trunk in each office, lines accessible to the switch 30 at one office, call registers individual to said lines accessible to the switch at the other office, an impulse sender at said other office, means responsive to the initiation of a call on one of said lines for causing said sender to transmit impulses to 35 both of said switches to set the switch at said one office into engagement with the calling line and to set the switch at the other office into engagement with the call register individual to the calling line.
- 40 7. A telephone system as claimed in claim 6 in which the impulse sender re-operates upon the termination of the call and transmits impulses to both switches to restore them to their normal positions.
- 45 8. In a telephone system, two offices connected by a trunk line, two switches associated with the trunk line at each office, lines accessible to the switches at one office, contacts individual to the lines accessible to the switches at the other office, means for simultaneously operating one of 50 the switches in each office to connect respectively with a calling line and a contact individual thereto, and means for simultaneously operating the other of the switches in the two offices to connect respectively with a called line and a contact individual thereto.
- 60 9. In a telephone system, two offices connected by a trunk line, two switches associated with the trunk line at each office, lines accessible to the switches at one office, contacts individual to the lines accessible to the switches at the other office, means responsive to a call on one of said lines for simultaneously operating one of the switches in each office to connect, respectively, with the 65 calling line and a contact individual thereto, means controlled over the calling line for designating a called line, and means for simultaneously operating the other switches in the two offices to connect, respectively with the line designated 70 and a contact individual thereto.
10. A telephone system as claimed in claim 9 in which the operation of the various switches is controlled by an impulse sender at one of the offices.
- 75 11. In a telephone system, a group of lines, two

switches having access to said lines, means for operating one of the switches to connect with a line on which a call has been initiated or with a line which is being called from a line outside of the group, means for operating the other switch 5 to connect with a line which is being called by another line in the group, and means for temporarily connecting said switches to complete a talking connection between calling and called lines in the group. 10

12. In a telephone system, a main office and a sub-office, a calling line and a called line at the sub-office, a switch at the sub-office having access to the called line, registering apparatus at the main office for registering the number of the 15 called line under control of the calling party, and means at the main office responsive to the registration of part of the called line number for testing for the idle or busy condition of said switch.

13. In a telephone system, two offices connected by a trunk, calling and called lines at one office, means for extending the calling line to the other office, means at said other office for registering the number of the called line, a switch at 20 said one office adapted to be directly operated under control of said last means to extend the connection to the called line, and means for preventing the directive operation of said switch in case the called line is busy.

14. In a telephone system, two offices, a calling 30 line and a called line at one office, means for extending the calling line to the other office, means at the other office for registering the number of the called line, and means at the other office controlled by said registering means for determining the idle or busy condition of the called line. 35

15. In a telephone system, two offices, a calling line and a called line at one office, means for extending the calling line to the other office, means at the other office for registering the number of 40 the called line, means at the other office for determining the idle or busy condition of the called line, and means effective provided the called line is idle for directly operating switching mechanism in accordance with the number registered 45 to extend a connection to the called line.

16. In a telephone system, a main office and a sub-office, calling and called lines at the sub-office, means for extending a calling line to the main office, registering means at the main office 50 controlled over the calling line for registering the digits of the called number, a switching device at the sub-office for extending a connection to the called line, means associated with said registering means for testing for the idle or busy 55 condition of said device prior to the registration of the last digit of the called number, and means associated with said registering means for testing for the idle or busy condition of the called line after the registration of the last digit of the 60 called number and prior to the operation of said device.

17. A telephone system as claimed in claim 16 in which a busy tone is returned to the calling party in case either the switching device at the 65 sub-office or the called line is found busy.

18. In a telephone system, two offices connected by a trunk line, a plurality of lines at one office, a switch terminating the trunk at said one office and having access to said lines, a set of terminals 70 for each of said lines at the other office, a second switch associated with the trunk at said other office and having access to said contact sets, means for extending a connection to one of said terminal sets, means responsive to the connection 75

- for causing said second switch to hunt for and connect with said one terminal set, and means for simultaneously operating the first switch to take up a position corresponding to that of the second switch and to extend a connection to the line corresponding to the terminal set. 5
19. In a telephone system, two offices connected by a trunk line, a plurality of lines at one office, a switch at said one office having access to said lines, a set of terminals for each line at the other office, a second switch at said other office having access to said terminal sets, an impulse sender at said other office, means for extending a connection to one of said terminal sets, means responsive to the connection for causing said sender to transmit impulses to both of said switches to set the same, and means responsive to the second switch engaging the terminal set to which the connection was extended for preventing the further operation of either switch. 15
20. In a counting device, a stepping switch, two relays, a relay for disabling said switch, a second relay and a third relay, a contact normally connected to said second relay and accessible to said switch, a second contact normally connected to said first relay and accessible to said switch, means for operating the switch to connect with said first contact to operate said second relay, and means controlled by said second relay for disconnecting itself from said first contact, for connecting the contact to said first relay, for disconnecting said second contact from said first relay, and for connecting the second contact to said third relay. 25
21. In a telephone system, a main office and a sub-office, trunks connecting the offices, subscribers' lines at the sub-office, a set of terminals at the main office for each of said lines, means responsive to the extension of a toll connection to one of said terminals for further extending the connection to a wanted line provided the same is busy, means for giving the calling toll operator a busy signal without extending the connection thereto in case the line is busy, means for giving the calling toll operator a busy signal without extending the connection thereto in case the line is idle and all of said trunks are busy, and means for giving the calling toll operator an all-trunks busy signal in case the operator attempts to offer the toll call to the wanted line when the line is idle and all of said trunks are busy. 35
22. In a telephone system, two offices connected by a trunk line, two switches associated with the trunk line at one office, a registering device associated with the trunk line at the other office, a calling line and a called line at said one office, means including one of said switches for extending the calling line to said registering device via the trunk line, means controlled over the calling line for setting said device in accordance with the number of the called line, means controlled by said device for operating the other of said switches in accordance with the setting of the device to extend a connection to the called line, a source of signalling current and means in said device for connecting it to the trunk line to signal the called line, and means responsive to the called subscriber answering for disconnecting said current source from the trunk line. 45
23. In a telephone system, two offices connected by a trunk line, two switches associated with the trunk line at one office, a registering device associated with the trunk line at the other office, a calling line and a called line at said one office, means including one of said switches for extending the calling line to said registering device via the trunk line, means controlled over the calling line for setting said device in accordance with the number of the called line, means controlled by said device for operating the other of said switches in accordance with the setting of the device to extend a connection to the called line, a source of signalling current and means in said device for connecting it to the trunk line to signal the called line, and means responsive to the called subscriber answering for disconnecting said current source from the trunk line. 50
24. In a telephone system, two offices connected by a trunk line, a switch associated with the trunk line at each office, subscribers' lines accessible to the line at each office, subscribers' lines accessible to the switch at one office, call registers and test contacts individual to said lines and accessible to the switch at the other office, means responsive to the initiation of a call on one of said lines for operating the switch at said one office to connect with the calling line, and means for simultaneously operating the switch at the other office to connect with the call register and test contact individual to the calling line. 55
25. In a telephone system, a group of lines, two switches having access to said lines, means for operating said switches to connect with any of said lines as calling or called lines, a third switch having access to said lines, means for operating said third switch to connect with any of said lines as called line, and means for temporarily associating said third switch with either one of said first two switches to complete a connection between two lines in the group. 60
26. In a telephone system, a main office and a sub-office, a calling line at the sub-office, switches at the sub-office, means including one of said switches for extending the calling line to the main office, subscriber controlled means at the main office for registering the digits of a called line number, and means responsive to the registration of sufficient digits to indicate that the called line is in the sub-office for causing said last means to test for an idle sub-office switch over which to complete the connection. 65
27. In a telephone system, a main office and a sub-office, a calling line at the sub-office, means for extending the calling line to the main office, a registering device at the main office, means controlled by the calling subscriber for setting said registering means in accordance with certain digits of a called line number, and means responsive to the setting of said registering means to indicate a call to another sub-office line for rendering the registering means effective to register a subsequent digit of the called number. 70
28. A telephone system as claimed in claim 16, in which means is provided for returning a busy tone to the calling party in case the switching device at the sub-office tests busy, and in which the registration of the last digit of the called number is prevented under these conditions. 75
29. In a telephone system, two offices connected by a trunk line, a plurality of lines at one office, a switch having access to said lines, a set of terminals for each of said lines at the other office, a second switch having access to said terminal sets, an impulse sender at the other office, means for extending a connection to one of said terminal sets, means responsive to the connection for causing said sender to transmit impulses to both switches to stop them simultaneously, and means 75

responsive to said second switch engaging the terminal set to which the connection was extended for disabling said sender and thereby stop the first switch in position to connect with the line 5 associated with said one terminal set.

30. In a telephone system, a sub-exchange, a trunk line extending from said sub-exchange to a main exchange, two switches terminating said trunk in the sub-exchange, means for operating 10 the first switch as a finder to extend a calling sub-exchange line to the main exchange, means for operating said first switch as a connector to complete a call from the main exchange to a sub-exchange line, and means controlled from the 15 main exchange for operating said second switch as a connector to complete a call to a sub-exchange line provided the calling line is also a sub-exchange line.

31. In a telephone system, a main exchange, a 20 sub-exchange, a trunk line connecting said exchanges, a switch terminating said trunk in the sub-exchange, an impulse sender in the main exchange, and means responsive to a call on a line in the sub-exchange for operating said sender to 25 send impulses over said trunk line to said switch to operate the same to find the calling line.

32. A telephone system as set forth in claim 31, in which impulses are transmitted over one conductor only and in which means in the switch 30 is provided for stopping the sending operation over the other conductor.

33. A telephone system as set forth in claim 31, in which the said switch is provided with a

test relay controlled over the two sides of the calling line in series to stop the sending operation.

34. In a telephone system, a main exchange, a sub-exchange, a trunk line connecting said exchanges, a switch terminating said trunk in the 5 sub-exchange, said switch having access to the lines in the sub-exchange, means for operating said switch as a finder to connect with a calling line or as a connector to connect with a called line, two auxiliary switches in the main 10 exchange, an impulse sender in the main exchange for transmitting the necessary impulses over the trunk line to the first switch to operate the same in either case, and arrangements whereby said impulse sender when transmitting impulses over 15 said trunk line, also transmits impulses to one or the other of said auxiliary switches depending on whether the first switch is being operated as a finder or as a connector.

35. In a telephone system, a calling and a 20 called line, means for connecting said lines, a common conductor connected to one conductor of the calling line and to one conductor of the called line, means for transmitting signalling current over said common conductor to said lines, a low 25 resistance connection between the other conductor of the called line and ground to provide a circuit for ringing the called subscriber's bell, and a high resistance connection between the other conductor of the calling line and ground to provide a circuit for producing a tone in the calling 30 subscriber's receiver.

HARRY G. EVERSON.
